SWEEPER

Norman W. Cummins, Louisville, Ky.

Application December 1, 1933, Serial No. 700,428

10 Claims. (Cl. 15—41)

This invention pertains to the structure of a running gear for use on portable carpet sweepers equipped with a rotary brush actuated by traction wheels.

5 In the general class of carpet sweepers in which this invention belongs, it has been standard practice to mount the supporting wheels on the ends of long shafts which extend through the dust arresting chamber. These shafts project beyond the end walls to provide axles on which to mount the wheels. It has been found desirable in such structures to enclose these shafts in ducts or casings to prevent the ingress of dust from the apertures in the end walls through which these shafts pass, also to protect these shafts from collecting dust, threads, etcetera. To prevent these shafts from rotating and throwing dirt on to the brush, which is fouled thereby, has been a problem not entirely mastered and a recognized source of annoyance, as well as a structural and operating problem. These shafts, also the enclosing ducts, have been found to be further objectionable as they interfered with free discharge, or dumping when an excessive accumulation of matter has been lodged in the dust chamber.

30 The principal object of this invention is to provide a carpet sweeper construction of a new order, wherein all of the above objections are entirely overcome, in the consummation of which a highly improved wheel action has been developed.

35 A further object is to construct the wheel supporting mechanism, the dust pan pivots and the dust pans on the two unitary duplicate plates, to insure maintaining the planned relation of the major constituent parts throughout the life of the machine.

40 A still further object is to protect the mechanism from external damage through the medium of a readily detachable hood or cover.

45 Other objects of the invention will be developed so as to be clearly understood by reference to the following specification and accompanying drawing in which is illustrated a preferred embodiment of those portions of the carpet sweeper required to disclose the invention.

Drawing

50 Figure 1 is a major portion of an end view of a carpet sweeper housing with the principal part of the mechanism cover removed to disclose the details of the mechanism. The wheels and rotating brush have been omitted for the sake of clearness.

Fig. 2 is a view of Fig. 1 as seen from the bottom with some sections and parts removed.

Fig. 3 shows a portion of a wheel in cross section as mounted on its axle and the supporting members which are shown in cross section, on an enlarged scale, the other adjacent parts not being indicated.

Fig. 4 is a front view of Fig. 3, with the wheel omitted.

Fig. 5 is a detail of a portion of one of the dust pans.

Structure

Numeral 10 indicates an end wall of the sweeper housing which is usually constructed of wood. 11 is the end plate referred to hereinafter as the "chassis" plate and which is mounted on 10 by screws 12. On this plate are mounted a number of parts as a sub-assembly which is used on both ends of the sweeper. Axle 13 is rigidly secured to plates 14 and 15 by the formation of head 13a, there being a spacer 16 of sufficient proportions to prevent these two plates from binding chassis plate 11, which 14 and 15 straddle, this assembly being such as to permit free vertical or horizontal movement. This axle assembly is given a normal position by the action of spring 17, which is permanently attached to the chassis plate 11 by spring clip 18.

It must be understood that both the right and left hand axle assemblies shown in Fig. 1 are to be regarded as the same. The right hand axle assembly is shown in full lines in its normal position, and the dotted line position that which it will assume when the sweeper is in operation and pressure is being applied by the operating handle which is not shown in the drawing. The part of the axle assembly shown in this figure at the left hand side discloses the opening 11a in the chassis plate to permit this travel.

Dust pans 20 are mounted on pivots 21, which are attached to the chassis plate. This assembly is effected incident to mounting the chassis 11 on to end walls 10 and results in the pans being suspended between these plates.

Each dust pan is kept in closed position by spring 22, each end of which contacts with the dust pan as shown. The apex of the spring is shown disposed in a hook of arm 23 which is fixed onto shaft 24, which in turn is pivotally mounted in bushing 24a secured in plate 11 and passes through housing end 10. Onto the other end of shaft 24 is fixed lever 25, to the lower end of same is pivoted arm 26 by pivot 27. This arm extends through notch 28, of mechanism cover 50 55

29 which functions as a guide or bearing for same. It will be perceived that by a squeezing action applied by a finger lodged against the 5 exposed end 26a of the cover and a thumb lodged on the exposed end 26a of arm 26 the linkage consisting of arms 26, 25 and 23 will cause spring 22 to be raised which in turn will pull on dust pans and result in simultaneously opening them for disposing of dust collected therein. Releasing 10 of this pressure permits spring 22 to return the parts to normal, as shown in the drawing.

It will thus be perceived that the chassis assembly is not only of pronounced utility in maintaining the several parts in definite relation, but 15 that it admits of a sub-assembly of these very important parts which is not only of great advantage to the manufacturer but to the user, should replacement ever be desired.

Attention is also directed to the feature where- 20 in the cover 29 protects the enclosed parts against mechanical damage and other elements, such as sunlight which is known to definitely age the rubber tires on the wheels. By removing screws 30 the entire cover 29 can be disassembled 25 from the sweeper and permit access for lubrication or repairs.

Scope

The drawing selected to disclose this invention and the specification thereof are in terms of my 30 improvements as incorporated into a sweeper having a wood housing. In the application of this invention to a unitary drawn metal housing, the separate chassis plates can be eliminated by mounting the axles and their plates 14, 15 together with the special spring clip 18 and the dust pan pivots directly in the ends of the housing with the dump lever bearing and mechanism on one end, substantially in accordance with the 35 teachings herein. Hence some of the claims are 40 directed to structure that will embrace either type of a sweeper carrying these improvements and also to directly read on other obvious modifications, rearrangements and eliminations which can be indulged without departing from 45 the spirit of my invention, therefore I wish to be limited only by the following claims:

I claim:

1. In a device of the class described, a chassis 50 plate, a pair of floating axles mounted in said plate, a resilient member anchored to said chassis plate and having a pair of arms pivotally engaging an extension of guide members rigidly secured to said axles for resiliently urging said axles downwardly and toward each other and to further prevent rotation of said floating axles.

2. In a carpet sweeper, the combination of a 55 chassis plate, an aperture in said chassis plate, a floating stub axle mounted for movement as limited by said aperture, guide plates rigidly secured to said axle and slidably engaging the opposite faces of said chassis plate to limit the movement of said axle to a vertical plane.

3. In a carpet sweeper, the combination of a 60 chassis plate, an aperture in said chassis plate, a floating stub axle mounted for movement as limited by said aperture, guide plates rigidly secured to said axle and slidably engaging the opposite faces of said chassis plate to limit the movement of said axle to a vertical plane, and 65 an extension on one of said guide members pivotally attached to the free end of a spring anchored to said chassis plate so as to prevent rotation of the axle while permitting lateral and

horizontal movement against the pressure of said spring.

4. In a carpet sweeper, the combination of a 5 chassis plate, an axle mounted in said chassis plate, a wheel rotatably mounted on said axle, a guide plate rigidly secured to said axle, and a resilient member anchored to said chassis plate and pivotally engaging said guide plate so as to prevent rotation of the axle in said chassis plate.

5. The combination with an article of the class 10 described including a chassis plate, a floating axle carried by said chassis plate and a wheel rotatably mounted on said axle, and means for preventing rotation of said axle comprising a 15 member rigidly secured to said axle having an extension pivotally engaged by the free end of a spring anchored to said chassis plate.

6. In a carpet sweeper, the combination of a 20 chassis plate, a floating axle mounted in said chassis plate, a wheel rotatably mounted on said axle, a guide plate secured to said axle and pivotally engaged by the free end of a spring anchored to said chassis plate so as to prevent rotation of the axle while permitting movement 25 thereof against the pressure of said spring.

7. In a carpet sweeper, the combination of a 30 chassis plate, a floating axle mounted in said chassis plate, a wheel rotatably mounted on said axle, a spring anchored to said chassis plate extending crosswise of said axle and pivotally attached to an extension of a guide member secured to said axle so as to yieldingly urge said 35 axle to move laterally and horizontally and prevent rotation of said axle while permitting lateral and horizontal movement against the pressure 40 of said spring.

8. In a carpet sweeper, the combination of a 45 chassis plate, a floating axle mounted in said chassis plate, a wheel rotatably mounted on said axle, a spring anchored to said chassis plate extending crosswise of said axle and pivotally attached to a guide member rigidly secured to said axle so as to yieldingly urge the said axle to move downwardly and prevent rotation of said axle while permitting lateral movement against the 50 pressure of said spring.

9. A carpet sweeper comprising a case, a horizontal rotatable brush in the case, an axle at one side and parallel to the axis of the brush, means to support the axle and maintain it in 55 said parallel relation while allowing it to move vertically and horizontally toward and away from the brush, a wheel mounted on said axle and frictionally driving the brush, an arm rigidly secured to the axle, a rod spring secured to the 60 sweeper case and a pivot securing said spring to said arm, said pivot being so placed that a line through the pivot and the axle passes under the brush.

10. A carpet sweeper comprising a case, a horizontal rotatable brush in the case, an axle on each side and parallel to the axis of the brush, means to support the axles and maintain them in 65 said parallel relation while allowing each to independently move vertically and horizontally toward and away from the brush, a wheel mounted on each axle and frictionally driving the brush, an arm rigidly secured to each axle, a rod spring secured to the sweeper case and a pivot securing each end of said spring to each 70 arm, said pivots being so placed that a line through each pivot and each axle will cross under the brush.
